UNITED STATES PATENT OFFICE.

WILLIAM EDWARD GLOVER, OF LENOIR CITY, TENNESSEE.

CAR-AXLE BOX.

1,102,042.

Specification of Letters Patent. Patented June 30, 1914.

Application filed July 5, 1913. Serial No. 777,549.

To all whom it may concern:

Be it known that I, WILLIAM EDWARD GLOVER, a citizen of the United States, residing at Lenoir City, in the county of Loudon and State of Tennessee, have invented a new and useful Improvement in Car-Axle Boxes, of which the following is a specification, reference being had to the accompanying drawing.

10 My improvement relates particularly to car axle boxes containing anti-friction rollers.

The object of the improvement is to provide such a car axle box formed of a small number of simple and durable parts.

15 In the accompanying drawings, Figure 1 is a longitudinal, upright section of a car axle box embodying my improvement; Fig. 2 is a section on the line, 2-2, of Fig. 1, looking toward the right; Fig. 3 is a section on the line, 3-3, of Fig. 1, looking toward the left; Fig. 4 is a section on the line, 4-4, of Fig. 1, looking toward the right.

20 Referring to said drawings, A is a car axle. This has a short neck, A¹, next to the body of the axle. Adjoining said neck is another neck, A², longer and smaller in diameter than the neck, A¹. Around the 25 outer end of the neck, A², is a flange, A³.

B, is the body of the axle box. This is of the usual form, open at its inner end and at its outer end and flat across the top. Above the outer portion of the neck, A¹, the box body has a groove, B¹, to receive the upper edge of the dust guard, D. Said guard surrounds the neck, A¹, and has an inward-directed flange, D¹, conforming to the surface of the neck, A¹. Said guard is divided on a horizontal line cutting the axis of the axle, thus forming an upper section, 1, and a lower section, 2. Said sections are drawn toward each other by two springs, 3, one located at one side and the other at the other side of said guard, and each having one end secured to the upper section and having its other end secured to the lower section of the guard by means of hooks, 4.

30 A sleeve or housing, C, surrounds the neck A², its inner end bearing against the dust guard, D. The interior of said sleeve is cylindrical and large enough to make room for anti-frictional rollers, R, between the inner face of said sleeve and the neck, A², with the proper engagement between

said sleeve, neck, and rollers. At the outer end of said sleeve, a wall, 5, extends downward over the outer end of the axle to approximately the middle of the latter. Said wall may be engaged for the insertion and removal of the sleeve, and it also serves as a means for excluding dust from the upper portion of the bearing. The top of said shell is of any suitable broadened form 60 adapting it to form a seat to receive the wedge, W, which is similar to the wedge heretofore used in securing the "brass" of a car axle box in common use. In the form shown in the drawings, the upper portion 65 of said sleeve has a middle, horizontal portion, 6, an outer horizontal portion, 7, along each edge, and an oblique portion, 8, between the portions, 7 and 6. The wedge conforms to the faces, 6, and 8, it having a middle 70 horizontal portion resting on the face, 6, and slanting portions, 10, resting on the faces, 8, 8. The upper portion, 9, rises between its ends so that the middle of said portion will bear against the upper wall of the 75 box body, B. Opposite the inner end of the wedge, the sleeve, C, has an upward-directed flange, 11, against which the inner end of the wedge bears.

When the parts are to be assembled, the 80 box body, B, is raised and the dust guard, D, placed around the neck, A², near the middle of the latter. Then the rollers, R, are inserted between said neck and the dust guard, the latter serving as an expansible, 85 band-form retainer for the rollers. The rollers being thus temporarily held, the sleeve, C, is now moved rearward around the neck, A², and around the series of rollers. When the inner end of the sleeve bears 90 against the dust guard, the latter slides inward until it entirely leaves the rollers and assumes its normal position on the neck, A¹. From what has been said, it will be seen that the dust guard is a temporary retainer of 95 the rollers, its function in this respect being to receive and hold the rollers in place until the sleeve, C, surrounds said rollers sufficiently to retain them. When the dust guard is in its normal position, its upper edge rests 100 in the groove, B¹. In such position, said guard forms a stop for the inner end of the sleeve, to prevent further inward movement. The wedge, W, is next inserted and moved 105 backward until its inner end bears against the flange, 11, on the sleeve. Then the engagement between said flange and the rear

end of the wedge prevents the forward movement of the sleeve. The sleeve is preferably made long enough to make the inner face of the wall, 5, (when said wall is present) clear the outer end of the axle when the inner end of the sleeve is held by the dust guard and the wedge, as above described.

It will be observed that the rollers, R, are held against inward movement by the neck, A¹, and against outward movement by the flange, A².

I claim as my invention:

1. In a structure of the nature described, the combination of an axle, a box body having means for engaging a dust guard, a dust guard surrounding said axle, rollers surrounding said axle, outward of said dust guard, a sleeve surrounding said rollers and axle and large enough to pass over the end of the axle, and having at its inner end a flange, and a wedge located between the upper portion of said sleeve and the upper portion of the box body and bearing endwise against said flange, substantially as described.

2. In a structure of the nature described, the combination of an axle, a box body, a dust guard surrounding said axle, rollers surrounding said axle outward of said dust guard, a sleeve surrounding said rollers and axle and large enough to pass over the end of the axle and having at its inner end a flange, a wedge located between the upper portion of said sleeve and the upper portion of the box body and bearing endwise against said flange, substantially as described.

3. In a structure of the nature described, the combination of an axle, a box body having means for engaging a dust guard, a dust guard surrounding said axle, rollers surrounding said axle outward of said dust guard, a sleeve surrounding said rollers and axle and large enough to pass over the end of the axle and having at its inner end a flange, a wedge located between the upper portion of said sleeve and the upper portion of the box body and bearing endwise against said flange, substantially as described.

4. In a structure of the nature described, an axle, a box body surrounding the axle, rollers surrounding the axle, a sleeve large enough to pass over the end of the axle and adapted to surround said rollers, a dust guard adapted to surround said rollers and to be pushed inward to its seat by said sleeve, substantially as described.

5. In a structure of the nature described, the combination of an axle, a box body having means for engaging a dust guard, rollers surrounding said axle outward of said engaging means, a dust guard adapted to surround said rollers and to be pushed therefrom to its seat, a sleeve large enough to pass over the end of the axle and adapted

to surround said rollers and axle and having at its inner end an upward-directed flange, and a wedge located between the upper portion of said sleeve and the upper portion of the box body and bearing endwise against said flange, substantially as described.

6. In a structure of the nature described, the combination of an axle, a box body, rollers surrounding said axle, a dust guard adapted to surround said rollers and to be pushed therefrom to its seat, a sleeve large enough to pass over the end of the axle and adapted to surround said rollers and axle and having at its inner end a flange, a wedge located between the upper portion of said sleeve and the upper portion of the box body and bearing endwise against said flange, substantially as described.

7. In a structure of the nature described, the combination of an axle, a box body having means for engaging a dust guard, rollers surrounding said axle, a dust guard adapted to surround said rollers and to be pushed from the latter to its seat, a sleeve large enough to pass over the end of the axle and adapted to surround said rollers and axle and having at its inner end an upward-directed flange, a wedge located between the upper portion of said sleeve and the upper portion of the box body and bearing endwise against said flange, substantially as described.

8. In a structure of the nature described, the combination of an axle, a box body having means for engaging a dust guard, rollers surrounding said axle outward of said engaging means, a sectional dust guard adapted to surround said rollers and to be pushed therefrom to its seat, a sleeve large enough to pass over the end of the axle and adapted to surround said rollers and axle and having an inner flange, and a wedge located between the upper portion of said sleeve and the upper portion of the box body and bearing endwise against said flange, substantially as described.

9. In a structure of the nature described, the combination of an axle, a box body, rollers surrounding said axle, a sectional dust guard adapted to surround said rollers and to be pushed from said rollers to its seat, a sleeve large enough to pass over the end of the axle and adapted to surround said rollers and axle and having at its inner end a flange, a wedge located between the upper portion of said sleeve and the upper portion of the box body and bearing endwise against said flange, substantially as described.

10. In a structure of the nature described, the combination of an axle, a box body having means for engaging a dust guard, rollers surrounding said axle, a sectional dust guard adapted to surround said rollers and to be pushed from the latter to its seat, a

sleeve large enough to pass over the end of the axle and adapted to surround said rollers and axle and having at its inner end a flange, a wedge located between the upper 5 portion of said sleeve and the upper portion of the box body and bearing endwise against said flange, substantially as described.

11. In a structure of the nature described, the combination of an axle, a box body having means for engaging a dust guard, rollers surrounding said axle outward of said engaging means, a dust guard adapted to surround said rollers and to be pushed therefrom to its seat, said dust guard comprising sections and yielding means tending to draw the sections toward each other, substantially as described.

12. In a structure of the nature described, the combination of an axle, a box body, 20 rollers surrounding said axle, a dust guard adapted to surround said rollers and to be pushed from said rollers to its seat, said dust guard comprising sections and yielding means tending to draw the sections toward each other, substantially as described.

13. In a structure of the nature described, the combination of an axle, a box body having means for engaging a dust guard, rollers surrounding said axle, a dust guard adapted 30 to surround said rollers and to be pushed from the latter to its seat, said dust guard

comprising sections and yielding means tending to draw the sections toward each other, substantially as described.

14. In a structure of the nature described, 35 an axle, a box body surrounding the axle, rollers surrounding the axle, a sleeve large enough to pass over the end of the axle and adapted to surround said rollers, a sectional dust guard adapted to surround said rollers 40 and to be pushed inward therefrom to its seat by said sleeve, substantially as described.

15. In a structure of the nature described, 45 an axle, a box body surrounding the axle, rollers surrounding the axle, a sleeve large enough to pass over the end of the axle and adapted to surround said rollers and to be pushed inward therefrom to its seat by said sleeve, said dust guard comprising sections 50 and yielding means tending to draw said sections toward each other, substantially as described.

In testimony whereof I have signed my name, in presence of two witnesses, this first 55 day of July, in the year one thousand nine hundred and thirteen.

WILLIAM EDWARD GLOVER.
